UNITED STATES PATENT OFFICE.

MAX W. FISCHER, OF PORTLAND, OREGON.

HINGE.

Application filed February 15, 1926. Serial No. 88,366.

My invention relates to hinges adapted to support heavy doors, for example, refrigerator doors. These doors in cold storage plants commonly weigh from five to six hundred pounds, and the stress and wear on their hinges is, in consequence considerable. At the same time, it is essential that the doors must close tightly against their frames to insure complete insulation of the interior of the refrigerator against exterior temperatures.

The usual practice is to provide hinges that will allow the doors to settle against the frame as it is closed, thus forming an air tight closure by the weight of the door bearing against the frame, such result being accomplished by the aid of a suitable cooperating latch; such for example as shown in my co-pending application for patent entitled Refrigerator door latch, filed Sept. 17, 1925, Serial No. 56,956.

To this end, it is necessary to provide a hinge permitting a slight vertical movement, attained by providing a cam surface on which some portion of the hinge bears and which raises and lowers the door as it is swung on its hinges.

The wear on these cam surfaces is rapid, and it has heretofore been necessary to replace an entire hinge when the cam-surface wears out.

This construction has also made it necessary that the hinges be made for right and left hand doors, and of extremely heavy construction.

The object of my invention is to provide a door hinge of which those parts bearing the greatest stress and the greatest wear are made of very hard metal, while the other parts are made of cheaper and readily machinable material. Also to provide a hinge which is relatively simple and not expensive to manufacture, and may be readily assembled.

This is not only important because it effects economy in the hinges, but also permits the hinge plate of said hinge to remain fastened to the door frame and thus the screw holes for said hinge do not become enlarged by removing and changing hinges.

A further object of my invention is to provide a hinge which is easily reversible; that is, it may be used for a right or left hand door, by merely substituting a right hand cam-plate for a left hand, or the reverse as the case may be.

A further object is to provide a hinge which may be adjusted vertically by the insertion of shims under the said cam-plate, thus to adapt the door for more perfect alignment with the frame. 60

A still further object is to provide a hinge of great strength, without so increasing its size as to make it unwieldy, and tend to restrict the movement of the door as opened 65 and closed.

I attain these and other incidental objects in a hinge comprising a hinge-plate provided with spaced hinge lugs, a hinged pintle removably secured in such lugs, a removable cam-plate mounted on said pintle over the lower of said lugs, and a friction-wheel, carried by the hinged strap, the said parts being arranged to permit the hinged-strap to be turned to a position approximately at right angles with the face of said hinged-plate. 70 75

The further details of construction and mode of operation are hereinafter described with reference to the accompanying drawings, in which:

Fig. 1 is an elevation of a portion of a door and its frame connected by my improved hinge;

Fig. 2 is a horizontal section through said door and its frame, and longitudinally through said hinge, said section being taken on the line 2-2 of Fig. 1; 80

Fig. 3 is an end elevation of the frame and the hinge mounted thereon taken in the direction of the arrow 3 in Fig. 1; 90

Fig. 4 is a fragmentary sectional view through a portion of said hinge taken on the line 4-4 of Fig. 3, and shows the construction of the removable cam plate; 95

Fig. 5 is a comparative view to Fig. 4, taken on the same line, showing an opposite-hand cam-plate in position;

Fig. 6 is a fragmentary view similar to Fig. 1 except that the hinged strap of said hinge is shown in dotted outline and the hinge plate which is affixed to the frame is shown in full lines, the cam plate is shown as being lifted relatively upon the pintle of the hinge by a relatively thick shim; 100 105

Fig. 7 is a view similar to Fig. 3 except that the door is shown as having been swung open; and

Fig. 8 shows a perspective view of a right hand cam-plate. 110

My invention is shown as being incorporated in a portion of a refrigerator structure

comprising a swinging door *a* and its frame *b*. Refrigerator doors and their frames are provided with weather stripping *c* which constitutes a seal between the same for minimizing heat losses. The providing of weather stripping in this manner however removes the support for said door which would otherwise be given by the frame. When the door is swung to, the cam-shaped devices, generally provided, tend to lower the same slightly, said cam-shaped elements thus serve as devices for moving and holding said doors in closed position.

My invention comprises a hinged strap *d* adapted to be fixed to the door *b* by screws *e* and *e'* and a hinge plate *f* fixed to the door frame by screws *g*.

The plate *f* is provided with spaced outstanding lugs *f'*, through which a pintle *h* is removably mounted therein, and secured by cotter pins *h'* at each end.

The end of the strap element *d* adjacent the door frame is thickened and provided with a hole *d'* in which the pintle *h* is journaled and by which the door is supported on the frame.

A recess *d*² is also provided in the lower end of the strap element, parallel to the hole *d'* in which a friction wheel *i* is mounted on a pin *i'*.

A cam plate *j*, Fig. 8, provided with a slot *j*² is adapted to be inserted over the pintle *h* and between the pintle and the plate *f*, the groove *j*² containing the spindle *h*, the said cam plate resting on the lower lug *f'*.

The cam-plate being held securely in place by the pintle and the straight edge *j*² which bears against the hinge plate, but which is easily removable by removing the pintle *h* from the hinge.

The cam-plate *j* is also provided on its upper face with an inclined surface *j*⁴ and the friction-wheel *i* will bear on said cam-plate so that as the door is swung on its hinges the wheel will travel on the inclined surface of the cam plate and raise and lower the door on the pintle *h*.

The cam-plate *j* and friction wheel *i* are made of very hard steel, as these two parts sustain all the wear, and thus the remainder of the hinge may be constructed of softer and more easily machined metal, which materially reduces the manufacturing costs without reducing the efficiency of the hinge.

The inclined surface *j*³ of said cam plate *j* is usually arranged so as to lower the door when it moves into closed position and thus said inclined surface normally tends to cause said door to swing closed. It is to be understood, however, that said cam plate might be arranged normally to cause said door to swing towards open position and normally to lift the same when said doors move into closed position.

Shims *k* may be placed under said cam

plate because the latter is movable upon said hinge and thus said door can be exactly alined with its frame by the use of shims, which is otherwise impossible if said cam plate is made as a portion of said hinge. 70 Said alinement, of course, may also be made by using cam plates of different thicknesses, although the former method is preferable because it permits the use of cam plates of uniform thickness. 75

The hinged strap *d* and the hinge plate *f* are exactly the same for left and right hand doors and thus if the hinges are to be used on a left hand door a cam plate such as *l* in Fig. 5, may be inserted in said hinge instead of the cam plate *j* Fig. 4, which will thus adapt said hinge to the opposite hand door. Said hinges are bi-symmetrical along their longitudinal axis which is substantially the line 2-2 in Fig. 1, and thus when a hinge is reversed from the position shown in Fig. 1, it need only be turned end for end and fixed in place.

As can be noted in Figs. 1 and 2, the wheel *i* is arranged in the longitudinal axis of the hinged strap. This permits the hinged strap *d* to be of substantially uniform thickness and width throughout its length, except for the thickened end portion in which the pintle *h* and friction wheel *i* is mounted. The placing of the roller in this manner not only does not weaken the hinged strap *d* but also permits said wheel to be placed closer to the pivot axis of said hinged strap, that is, closer to the pintle *h* and thus increases its strength materially. 95

I claim:

1. A hinge comprising a hinge-plate provided with spaced hinge lugs, a hinged pintle removably secured in such lugs, a removable cam-plate mounted on said pintle over the lower of said lugs, a hinged-strap journaled on said pintle, a friction wheel, carried by the hinged strap adjacent the pintle bearing on said cam-plate, and the said parts being arranged to permit the hinged-strap to be turned to a position approximately at right angles with the face of said hinged-plate. 105

2. A hinge comprising a hinge-plate provided with spaced hinge lugs, a hinged pintle removably secured in such lugs, a removable cam-plate mounted on said pintle over the lower of said lugs, a hinged-strap journaled on said pintle, said hinged-strap provided with a recess parallel with and adjacent to said pintle, a friction wheel, carried by the hinged strap in said recess, and the said parts being arranged to permit the hinged-strap to be turned to a position approximately at right angles with the face of said hinged plate. 115

3. A hinge comprising a hinge-plate provided with spaced hinge-lugs, a hinged pintle removably secured in such lugs, a removable cam-plate mounted on said pintle over

the lower of said lugs, a hinged-strap journaled on said pintle, a friction wheel, carried by the hinged strap adjacent the pintle, bearing on said cam-plate, and said hinge lugs projecting a substantial distance beyond the face of the hinge-plate, and the latter being cut away opposite said pintle whereby the hinged-strap may be turned to a position approximately at right angles to the face of the said hinged-plate.

4. A hinge comprising a hinge-plate provided with spaced hinge lugs, a hinged pin-

tle removably secured in such lugs, a removable cam-plate mounted on said pintle over the lower of said lugs, a hinged-strap journaled on said pintle, a friction wheel, carried by the hinged strap adjacent the pintle, bearing on said cam-plate, and the said parts being arranged to permit the hinged-strap to be turned to a position approximately at right angles with the face of said hinged-plate.
